FIG.3.

UNITED STATES PATENT OFFICE.

CLARK F. RIGBY, OF BUTLER, PENNSYLVANIA.

SUCKER-ROD.

1,357,475.

Specification of Letters Patent.

Patented Nov. 2, 1920.

Application filed May 23, 1919. Serial No. 299,358.

To all whom it may concern:

Be it known that I, CLARK F. RIGBY, a citizen of the United States, and a resident of Butler, in the county of Butler and State 5 of Pennsylvania, have made a new and useful Invention in Sucker-Rods, of which the following is a specification.

My invention relates to sucker rods for deep wells and comprises an improved form 10 of hollow tube adapted to be used for that purpose. The object of my invention is to secure strength, rigidity and lightness as well as to reduce the cost of such equipment and its operation.

15 In the accompanying drawings, Figure 1 is a vertical section through a portion of a drilled well equipped with my improved rod; Fig. 2 is an enlarged view of and vertical section through my rod and Fig. 3 is 20 a horizontal section on line 3—3 of Fig. 2.

Fig. 1 shows two sections, 1 and 2, of the well casing connected by a coupling 3. Operating within this casing is the reciprocating sucker rod made in convenient lengths 4. 25 Each length 4 is coupled to the adjacent length above and below by joint heads 5 and 6 respectively. The adjacent lengths, only one of which is shown, have co-operating joint heads 6 and 5 respectively. Heads 5 30 and 6 form a coupling which is described and claimed in United States Letters Patent 1,250,509 issued to me December 18, 1917. I wish to be understood as using this coupling for illustrative purposes only as many other 35 kinds of couplings may be substituted and my present invention involves the rod irrespective of the coupling means.

Each length 4 of the sucker rod is hollow and formed with substantial external and 40 internal longitudinal corrugations 7 which extend from end to end of the length of rod. These corrugations greatly stiffen the rod laterally and enable it to withstand much greater longitudinal compression than a 45 plain tube of equal diameter and thickness or than a solid rod of the usual type and of approximately the same weight.

The ends of sucker rod length 4 are completely filled by the pintles 8 of the joint 50 heads. I make the union between rod length 4 and each head 5 or 6 airtight, preferably by welding the rod to the head. When operating at considerable depth in a column 55 of oil or water or both, in addition to the lightness of material due to the tubular construction of the sucker rod, this type of rod

is decidedly buoyant because of the confined air. These two features greatly reduce the cost of operating the rod, as will be appreciated readily when it is understood that the 60 well may be several thousand feet deep.

Tubular sucker rods effect a saving over solid rods in first cost, in handling and in operation, but heretofore such rods have been so weak throughout, especially at their 65 threaded ends, that in handling and operating them they buckled and otherwise failed, sometimes from their own weight when supported at their center. My corrugated tubular rod has sufficient strength to endure 70 ordinary stresses yet retains the essential feature of lightness which is present in plain tubular rods.

In addition to the advantages of the tubular, air-tight construction and to assist the 75 corrugated surfaces in withstanding the heavy pressure of a column of liquid a couple of thousand feet high, I introduce into lengths 4 air under pressure greater than the atmospheric pressure. The confined, compressed air will withstand the 80 inward pressure of the column of liquid and thereby further strengthen the corrugated tube. This outward pressure of the confined air may be varied according to the depth at 85 which the length is to operate.

I claim:

1. A sucker rod consisting of an air-tight cylinder filled with air above atmospheric pressure.

2. A sucker rod comprising a longitudinally corrugated tube having its ends sealed air-tight by coupling members and its walls supported internally by air under compression sufficient to withstand the external pressure of liquid in which the sucker rod is to be operated.

3. A sucker rod consisting of an air-tight cylinder filled with air under pressure approximating the external pressure on the rod 100 when operating in a well.

4. In apparatus for deep wells, a plurality of sucker rod sections each consisting of an air-tight cylinder filled with air under pressure, said pressure in different rods increasing with substantial increases in the depth of the rod from the mouth of the well.

In testimony whereof, I have hereunto subscribed my hand this 12th day of May, 1919.

CLARK F. RIGBY.
